(57) **CLAIM**

The ornamental design for a dispensing bottle, as shown and described.

DESCRIPTION

FIG. 1 is a front perspective view of a dispensing bottle according to the present invention shown with a spout retracted;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof.

FIG. 8 is a front perspective view of the dispensing bottle with the spout extended; and,

FIG. 9 is a top view thereof.

Portions of the dispensing bottle shown in broken lines form no part of the claimed design.

1 Claim, 5 Drawing Sheets
